US00D337572S

United States Patent [19]

Bowen et al.

[11] Patent Number: Des. 337,572

[45] Date of Patent: ** Jul. 20, 1993

[54] COMPUTER CABINET

[75] Inventors: **Stephen A. Bowen; Melvin C. August,** both of Chippewa Falls; **Stephen Cermak, III,** Elk Mound; **David R. Collins,** Eau Claire; **Mary A. Nebel;** **Stephen E. Nelson,** both of Chippewa Falls, all of Wis.; **Eugene N. Reshanov,** Golden Valley; **Eric J. Mueller,** St. Paul; **Danny J. Cunagin,** Minneapolis, all of Minn.

[73] Assignee: **Cray Research, Inc.,** Eagan, Minn.

[**] Term: **14 Years**

[21] Appl. No.: **908,029**

[22] Filed: **Jul. 2, 1992**

CLAIM

The ornamental design for a computer cabinet, as shown and described.

DESCRIPTION

FIG. 1 is a front and upper right side perspective view of a computer cabinet showing our new design; FIG. 2 is a lower right side perspective view thereof; FIG. 3 is a rear and upper left side perspective view thereof;

FIG. 4 is a top plan view thereof;

FIG. 5 is a front elevational view thereof;

FIG. 6 is a rear elevational view thereof;

FIG. 7 is a left side elevational view thereof; and,

FIG. 8 is a right side elevational view thereof.

The connecting cabinet is shown in broken lines in the figures for illustrative purposes only and forms no part of the claimed design.

FIG. 1

FIG. 2

FIG. 3

FIG. 4
